UNITED STATES PATENT OFFICE.

RAYMOND W. CHAMPION, OF PHILADELPHIA, PENNSYLVANIA.

WEATHER SEAL FOR THRESHOLDS.

Application filed March 19, 1921. Serial No. 453,620.

To all whom it may concern:

Be it known that I, RAYMOND W. CHAMPION, a citizen of the United States, residing at Philadelphia, in the county of Philadelphia, State of Pennsylvania, have invented a new and useful Weather Seal for Thresholds, of which the following is a specification.

My invention relates to improvements in weather seals for thresholds or sills. The object is to provide a sealing strip or bar stop, adapted to be operated by the closure, such as a door or a hinged sash or casement, when moved into the closing position to form a weather-tight or sealed closure between the movable and stationary parts, my said improvement being applicable to closures opening either inwardly or outwardly.

Referring to the drawings which illustrate merely by way of example a suitable embodiment of my invention:

Fig. 1 is a vertical cross-section showing the stationary sill and the lower end of the closure in closed position.

Fig. 2 is a similar view showing the elements in partly open position.

Fig. 3 is a horizontal section of same on a reduced scale.

Fig. 4 is a view in perspective of one end of the rotatable strip.

Fig. 5 is a plan view showing the invention applied to a double door or casement.

Fig. 6 is an elevation of the same showing one pivoted bar up and the other bar down.

Fig. 7 is a cross-section on line 7-7 of Fig. 6 on an enlarged scale.

Similar numerals refer to similar parts throughout the several views.

Referring especially to Figs. 1 and 2, the stationary sill 8 is preferably of metal and is provided with the channel 9 extending longitudinally approximately the entire length of the sill. The strip or bar 10 is pivotally supported in this channel on the stationary pivots 11 and 12. I have shown as a convenient construction whereby one end of the bar is inserted into the channel 9 with the pin 11 projecting in a corresponding aperture in the end of the bar 10; the other end of the bar 10 is provided with a slot and aperture formation 13, as shown in Fig. 4, for engaging the pin 12 when the bar has assumed the substantially horizontal position.

The bar has a rotary movement on said pivots from the position shown in Fig. 2, where the top of the bar lies flush with the top surface of the sill, to the position shown in Fig.

1, where one edge of the bar projects above the top surface of the sill.

The closure 14 is provided with the channel 15 in its lower edge; having the vertically disposed side wall 16 adapted to engage with the side of the bar 10 when the bar is in the elevated position as shown in Fig. 1. It will also be noted that the channel 9 is so formed as to have a side wall 17 adapted to engage with a cooperating lower side wall 18 of said bar 10. Suitably secured to the lower edge of closure 14 is the toe 19 having the upwardly extending bevelled surface 20. This toe projects beneath the channel 15. A corresponding slot 21 is provided in the upper surface of the sill to permit the movement of this toe therethrough when the closure moves into the closing position. In moving into the closing position the bevelled surface 20 engages a cooperating bevelled surface 22 provided in a slotted portion 23 of bar 10. This starts a rotative movement of bar 10 as the closure approaches the closing position. This movement is continued by the engagement with said surface 22 of the bar 10 by the end of the toe 19 to complete the quarter turn rotative movement of the bar 10 into the position shown in Fig. 1. In the position shown in Fig. 1, the opposite upper and lower margins or sides of bar 10 engage cooperating wall surfaces of the closure 14 and sill member 8. When the closure is moved into the open position, the wall 16 engaging with the upper side of bar 10, carries the same into the lower position that is with the top surface of bar 10 flush with the top surface of the sill as shown in Fig. 2. The groove 24 on one side of the channel 15 of closure 14 serves to prevent binding of the closure element with the bar 10 as the elements are moved from one position to the other; it also serves to deflect any moisture that might accumulate adjacent the lower edge of the closure and bar 10 into the channel 9. Seep holes or channels 25 and 26 are provided to drain any accumulation of moisture from the channel 9. Where both sets of seep holes or drain channels 25 and 26 are provided the device is obviously adapted to work in either direction to accommodate structures used in connection with inwardly or outwardly opening closures.

Where it is desired to use my invention in connection with double doors or double casements I provide a two section bar 27, 28. The sections are provided at their outer

ends, that is the ends towards the jambs or framework, with the openings or recesses similar to 13 shown in Fig. 4. The inward or adjacent ends of the strips however are 5 adapted to overlap as indicated in Figs. 5 and 6 and are supported by means of pins 29 carried by lugs 30 suitably secured to the sill as shown in Fig. 7. In connection with this 10 arrangement the bars 27, 28 are each provided with an aperture 31 with a suitable hole at one end of each. Each of these apertures 31, has a length equal to the combined length of the pin 29 and supporting lug 30, so that when the strip is moved into the 15 channel the lug and pin pass into the recess 31. The strip is then shifted so that the pin enters the hole in the end of said recess. The opposite end of the bar is then secured to its supporting pin, by means of the recess such 20 as 13 shown in Fig. 4.

In operation one closure, for example 32, must close before the other closure 33. In the closing movement of closure 32, bar 27 is elevated in the same manner as shown in 25 Fig. 1. When closure 33 is brought into the closed position, bar 28 is similarly elevated. The channel of closure 32 already being in position presents no obstruction to the elevation of bar 28.

In the closed position of either single or 30 double closures, the bar or bars are positioned as above described and shown in Fig. 1, one upper side of the bar engaging the side wall of the closure channel, the lower 35 opposite side wall of the bar engaging a side wall of the sill channel, thus forming an absolutely tight water and wind stop beneath the door or casement, or other closure. Water or wind beating beneath the door or 40 sash strikes the stop bar and goes down into the channel in the sill, and the water leaks out through the seep holes 25, or 26 as the case may be. Thus a circulation is permitted but always kept on the exterior. The 45 stop bar is easily removable to give ready access for clearing the sill channel when it is so desired.

What I claim is:—

1. A weather seal for a closure construction, comprising a closure and a sill, the closure provided in its lower edge with a channel extending the length thereof, the sill provided with a longitudinal channel having its upper longitudinal side margins in substantially the same horizontal plane, a bar supported intermediate its side margins on pivots located within the sill channel and adapted to lie with its top surface flush with 55 said longitudinal side margins to form a substantially continuous horizontal surface therewith, and adapted to be moved by the closure into a vertical position with a substantial part above the pivot and a substantial part below the pivot and elevating means mounted on said closure for raising 60 and maintaining said bar in such vertical position.

2. A weather seal for a closure construction, comprising a closure and a sill, the closure provided in its lower edge with a channel extending the length thereof, the sill provided with a longitudinal channel having its upper longitudinal side margins in substantially the same horizontal plane, a bar supported intermediate its side margins on pivots located within the sill channel and adapted to lie with its top surface flush with 70 said longitudinal side margins to form a substantially continuous horizontal surface therewith, and adapted to be moved by the closure into a vertical position with a substantial part above the pivot and a substantial part below the pivot so that one side of the part above the pivot will engage a side of the closure channel and elevating means mounted on said closure for raising and maintaining said bar in such vertical position.

3. A weather seal for a closure construction, comprising a closure and a sill, the closure provided in its lower edge with a channel extending the length thereof, the sill provided with a longitudinal channel having its upper longitudinal side margins in substantially the same horizontal plane, a bar supported intermediate its side margins on pivots located within the sill channel and adapted to lie with its top surface flush with 75 said longitudinal side margins to form a substantially continuous horizontal surface therewith, and adapted to be moved by the closure into a vertical position with a substantial part above the pivot and a substantial part below the pivot so that one side of the part above the pivot will engage a side of the closure channel and elevating means mounted on said closure for raising and maintaining said bar in such vertical position.

3. A weather seal for a closure construction, comprising a closure and a sill, the closure provided in its lower edge with a channel extending the length thereof, the sill provided with a longitudinal channel having its upper longitudinal side margins in substantially the same horizontal plane, a bar supported intermediate its side margins on pivots located within the sill channel and adapted to lie with its top surface flush with 80 said longitudinal side margins to form a substantially continuous horizontal surface therewith, and adapted to be moved by the closure into a vertical position with a substantial part above the pivot and a substantial part below the pivot so that one side of the part above the pivot will engage a side of the closure channel and elevating means mounted on said closure for raising and maintaining said bar in such vertical position.

4. A weather seal for a closure construction, comprising two closure elements and a sill, the closure elements provided in their lower edges with channels extending the length thereof and adapted to register with each other, the sill provided with a channel having its upper longitudinal side margins in substantially the same horizontal plane and adapted to register substantially with the closure channels, bars pivotally supported end to end in the sill channel having overlapping portions at the middle part of said channel, and forming together a surface 90 adapted to lie horizontally and flush with said side margins and also adapted to assume the vertical position projecting into the closure channels with faces engaging the side margins of said channels.

5. A weather seal for a closure construc-

tion, comprising two closure elements and a still, the closure elements provided in their lower edges with channels extending the length thereof and adapted to register with each other, the sill provided with a channel having its upper longitudinal side margins in substantially the same horizontal plane and adapted to register substantially with the closure channels, bars pivotally supported end to end in the sill channel having overlapping portions at the middle part of said channel, and forming together a surface adapted to lie horizontally and flush with said side margins and also adapted to assume the vertical position projecting into the closure channels with faces engaging the side margins of said channels, the pivotal support of said bars including pivot and recess means located within said bars a short distance from their overlapping ends.

15 20 25

20 25

6. A weather seal for a closure construction, comprising two closure elements and a sill, the closure elements provided in their lower edges with channels extending the length thereof and adapted to register with each other, the sill provided with a channel having its upper longitudinal side margins in substantially the same horizontal plane and adapted to register substantially with the closure channels, bars pivotally supported end to end in the sill channel having overlapping portions at the middle part of said channel, and forming together a sur-

face adapted to lie horizontally and flush with said side margins and also adapted to assume the vertical position projecting into the closure channels with faces engaging the side margins of said channels, the pivotal support of said bars including pivot and recess means located within said bars a short distance from their overlapping ends.

7. A weather seal for a closure construction, comprising two closure elements and a sill, the closure elements provided in their lower edges with channels extending the length thereof and adapted to register with each other, the sill provided with a channel having its upper longitudinal side margins in substantially the same horizontal plane and adapted to register substantially with the closure channels, bars pivotally supported end to end in the sill channel having overlapping portions at the middle part of said channel, and forming together a surface adapted to lie horizontally and flush with said side margins and also adapted to assume the vertical position projecting into the closure channels with faces engaging the side margins of said channels, the pivotal support of said bars including pivot and recess means located within said bars a short distance from their overlapping ends.
